(57) **CLAIM**

The ornamental design for a housing for computer modules, as shown and described.

DESCRIPTION

FIG. 1 illustrates a top, perspective view of the housing in accordance with the design. The dashed lines represent a computer module that is typically coupled to the housing. FIG. 2 illustrates a front elevation view of the housing in accordance with the design. The dashed lines represent a computer module that is typically coupled to the housing. FIG. 3 illustrates a left elevation view of the housing in accordance with the design. The dashed lines represent a computer module that is typically coupled to the housing. FIG. 4 illustrates a right elevation view of the housing in accordance with the design. The dashed lines represent a computer module that is typically coupled to the housing. FIG. 5 illustrates a top plan view of the housing in accordance with the design. The dashed lines represent a computer module that is typically coupled to the housing.

FIG. 6 illustrates a bottom plan view of the housing in accordance with the design. The dashed lines represent a computer module that is typically coupled to the housing. FIG. 7 illustrates a back elevation view of the housing in accordance with the design. The dashed lines represent a computer module that is typically coupled to the housing. FIG. 8 illustrates a front, bottom perspective view of the housing in accordance with the design. The dashed lines represent a computer module that is typically coupled to the housing.

FIG. 9 illustrates a front, bottom view of the housing in accordance with the design. Both a computer module and a fan that can be added to the housing are represented with dashed lines; and,

FIG. 10 illustrates a top, right perspective view showing two housing units combined into a half circle in accordance with the design. The dashed lines represent a computer module that is typically coupled to the housing.
